UNITED STATES PATENT OFFICE.

JOSEPH ALBERT RONCHETTI, OF WOONSOCKET, RHODE ISLAND, ASSIGNOR, BY MESNE ASSIGNMENTS, TO THE NOISELESS TYPEWRITER COMPANY, OF MIDDLETOWN, CONNECTICUT, A CORPORATION OF CONNECTICUT.

LINE-SPACING MECHANISM FOR TYPE-WRITING MACHINES.

1,162,192.

Specification of Letters Patent. Patented Nov. 30, 1915.

Application filed June 5, 1908. Serial No. 436,751.

To all whom it may concern:

Be it known that I, JOSEPH A. RONCHETTI, a subject of the King of Italy, residing at Woonsocket, in the county of Providence and State of Rhode Island, have invented 5 certain new and useful Improvements in Line-Spacing Mechanism for Type-Writing Machines, of which the following is a full, clear, and exact description, such as will enable others skilled in the art to which it 10 pertains to make and use the same.

My invention relates to the line spacing mechanism of typewriting machines and has for its object to provide mechanism for that 15 purpose which is practically noiseless in operation, and, further, to provide improved means for causing the platen roll to register with the lines and for freeing it to permit universal spacing.

20 In the accompanying drawings, wherein is illustrated one of the various possible embodiments of my invention, Figure 1 is an elevational view showing the same, the view being taken substantially on line 1—1, of 25 Fig. 2; Fig. 2 is a side view thereof looking from the left-hand end of Fig. 1; Fig. 3 is a sectional view showing the ratchet wheel 30 release devices, the view being taken on line 3—3 of Fig. 1; Fig. 4 is a view showing the parts positioned upon the left-hand end of 35 the carriage but in a different position; Fig. 5 is a view upon an enlarged scale taken substantially on line 5—5 of Fig. 1; Fig. 6 is an end view upon an enlarged scale; and 40 Fig. 7 is a similar front view of a device for controlling the position of the line-space pawl; Fig. 8 is an enlarged sectional view taken on line 8—8 of Fig. 1, showing the manner of supporting and adjusting the 45 alining scale. Fig. 9 is a view in elevation of a different embodiment of alining scale.

Similar reference characters refer to similar parts in the several views of the drawings.

45 Referring now to the drawings, 1 denotes a portion of the center tie-rod which extends transversely of the machine and forms a support for the platen carriage and associated mechanism. This center tie-rod is 50 provided with an upwardly extending portion or horn 2 against which the platen carriage 3 rests, said platen carriage being mounted upon rail 4 which extends longitudinally of the machine and upon which

it rides for letter-spacing, said rail being 55 vertically movable to shift the platen for different case printing.

A paper carrier in the present embodiment consisting of a platen roller 5 is mounted upon a shaft 6 journaled in the 60 side members 7 of the platen frame, said shaft being provided at its ends with knobs, one of which is shown at 8, by means of which the platen roll may be rotated. The platen which, in the present instance is 65 constituted by a thin strip of metal 10, which has a front plane face for receiving the types and a rear curved face to conform with the contour of the platen roll, is mounted upon the platen frame and supported 70 thereon at its ends by the side members 7 thereof; see Figs. 1 and 2.

75 11 denotes an actuating member in the form of a ratchet wheel which is mounted upon shaft 6 of the platen roll and is provided with crown ratchet teeth 12, and also has a plurality of peripheral teeth 13 which are disposed circumferentially about the same, the spaces between said teeth forming notches.

80 Supported by means of a pivot screw 15 (see Fig. 1) upon an ear 16 secured to the left-hand end of the platen carriage, about which it oscillates, is an actuating or line-space lever 17, said lever being held in the 85 position shown in Fig. 1 of the drawings, by means of a retractile spring 18 connected with an ear 20 formed upon the line-space lever adjacent the pivot thereof and also connected with a lug 21 formed upon a 90 bracket which supports ear 16. A pawl 22 is pivotally attached to the line space lever by means of a pivot screw 23 and between this pawl and the lever, and held in position by means of the pivot screw 23 is a friction 95 ring or member which is in the present instance a spring washer 24.

99 In order to maintain the end 25 of pawl 22 adjacent the teeth 12 of the ratchet wheel, but out of contact therewith when said pawl 100 occupies its normal position, a link 26 is pivotally attached, as at 27, to the platen carriage and has its opposite end hooked, as at 28, to enter an elongated recess 30 provided in the pawl. The spacing of the 105 ratchet wheel is regulated by means of a gage stop 31 which is fixed upon a pin 32 journaled in a bracket 33 carried by the line-

space lever, said stop gage in the present instance being held in one of several adjusted positions by means of a spring pin 34 engaging suitably spaced notches in bracket 33. 5 The end 35 of this gage stop engages the rear face of the pawl 22 when the same has been engaged with the teeth of the ratchet wheel during an actuation of the line-space lever and limits the throw of the pawl in 10 accordance with the particular position in which said gage stop is adjusted upon the line-space lever. In the present instance, notches 36 are provided in the back of the pawl 22 with which the end 35 of the gage 15 stop engages. The throw of the pawl 22 may therefore be regulated for any desired number of spaces.

In order to register the platen roll correctly after rotation, a detent 37 is provided, 20 said detent being a roller journaled in ears 38 provided upon a spring 40, said spring being provided with elongated slots 41 for receiving screws 42, by means of which it is adjustably fastened to the platen carriage. 25 Roller 37 engages with the peripheral notches 14 of the ratchet wheel and registers the platen roll in a manner which will be readily understood. The slots 41 which are provided in the spring 40 permit of the 30 forward and backward adjustment of the detent, whereby the teeth 12 of the ratchet wheel may be carried to such positions as to be in proper relation to the end of the line-space pawl 22. In order to release the 35 spring-pressed detent from the notches 14 of the ratchet wheel, a lever 43 is journaled upon the shaft 6 of the platen roll, said lever being provided with a handle 44, by means of which the same may be manipulated. 40 Lever 43, in the present instance, is provided with notches 45 and 46, which engage with one of the ears 38 of the detent supporting spring 40. When notch 45, which is the deeper of the two, is in engagement with an 45 ear 38, the detent is in engagement with the notches of the ratchet wheel, but when lever 43 is swung to the position shown in Fig. 3 of the drawings, notch 46 engages the ear 38 and lifts the detent out of engagement 50 with said notches and frees the ratchet wheel, whereby the platen roll may be freely rotated for universal spacing. Ears 47 and 48 are provided upon lever 43 for preventing an over-throw thereof in either direction. 55 50 denotes the alining scale member which is provided with an alining edge 51, a cut-away portion 52 and a projecting ear 53. The alining scale member is provided with a pair of depending arms 54 which are 60 pivoted upon screws 55 threaded in the ends of a supporting shaft 56, the latter being fixed as by means of a set screw 57 in the center tie-rod 1. Screws 55 are mounted eccentrically in the ends of shaft 56 in order 65 to enable the alining scale member to be ad-

justed vertically by rotation of shaft 56 (see Fig. 8), after which said shaft may be held in fixed position by means of the set screw 57. The edge 51 of the alining scale member may be graduated as shown, if desired. 70

In Fig. 2 of the drawings the alining scale 50 is shown as being inclined toward the platen and rests thereagainst, being held in such position by gravity. In Fig. 9, however, the line scale member is pivoted substantially below the platen and is held thereagainst by means of a leaf spring 58. The alining scale mechanism shown in the drawings and above described forms the subject-matter of a divisional application. 75

Having thus described the construction of this embodiment of my invention, the operation thereof may now be understood. Whenever the line-space lever 17 is actuated, pawl 22 being frictionally connected therewith will be swung into engagement with the teeth 12 of the ratchet wheel, whereupon during a further swinging movement of the line-space lever, the ratchet will be rotated until the end 35 of the stop gage 31 is engaged with one of the notches 36 of said pawl to limit the throw thereof. Upon the return movement of the line-space lever to normal position, the pawl 22 will be instantly disengaged from the teeth of the ratchet wheel, and the point thereof will be moved downward substantially in a straight line by means of the link 26 which connects the pawl with the platen carriage. When the line-space lever has returned to its normal position, the end 25 of the pawl will be adjacent to the teeth of the ratchet wheel but out of contact therewith, as shown in Fig. 1 of the drawings. When it is desired to release the platen roll for universal spacing, it 100 is merely necessary to rotate lever 43 to engage the notch 46 thereof with the ear 38 of the detent supporting spring, whereupon the detent 37 will be lifted beyond the peripheral teeth 14 of the ratchet wheel. 105

It will accordingly be seen that I have provided mechanism well adapted to attain, among others, all the ends and objects above pointed out, in an exceedingly simple yet efficient manner. Since the feed pawl is 110 normally disengaged from the ratchet wheel and is in engagement therewith only when the platen is engaged for line-spacing, the entire line-spacing operation is accomplished with the production of very little noise, there being no dragging or clicking of the teeth of the end of the pawl over the teeth of the ratchet wheel. 115

As many changes could be made in the above construction and many apparently 120 widely different embodiments of this invention could be made without departing from the scope thereof, it is intended that all matter contained in the above description or 125 shown in the accompanying drawings shall 130

be interpreted as illustrative and not in a limited sense.

Having described my invention, what I claim as new and desire to secure by Letters 5 Patent is:

1. In a typewriting machine, the combination with the platen carriage, of a platen roll journaled therein, a ratchet wheel carried by said platen roll, a line-space lever mounted to swing upon said platen carriage, a pawl pivotally mounted upon said line-space lever and adapted to be swung into engagement with the teeth of said ratchet wheel, means mounted on said lever for 15 varying the throw of said pawl, and means connecting said pawl with a fixed portion of the platen carriage for holding the former adjacent the teeth of said ratchet wheel. 75
2. In a typewriting machine, the combination with the platen carriage, of a platen roll journaled therein, a ratchet wheel mounted upon said platen roll, a line-space lever swiveled upon the platen carriage, a pawl pivoted upon said line-space lever normally 20 maintained out of engagement with the teeth of said ratchet wheel, but adapted to be swiveled into engagement therewith when said line-space lever is actuated, and a movable link connecting said pawl with a fixed portion 25 of said platen carriage for maintaining the same operative position closely adjacent said ratchet wheel. 85
3. In a typewriting machine, the combination with the carriage, of a platen roll mounted thereon, a ratchet wheel on said roll, a line-space lever swiveled upon the platen carriage, a pawl swiveled upon said line-space lever and normally held out of contact with said ratchet wheel but adapted 30 to be thrown into engagement therewith when said line-space lever is actuated, whereby said ratchet wheel will be rotated, and a link pivotally attached to the platen carriage and having an end thereof extended 35 to a slot provided in said pawl, said link being adapted to hold said pawl adjacent to said ratchet wheel when said line-space lever is in normal position. 95
4. In a typewriting machine, the combination with the platen carriage, of a platen roll journaled therein, a ratchet wheel mounted upon said platen roll, a line-space lever pivotally mounted upon said platen carriage, a pawl pivotally mounted upon 40 said line-space lever and normally held out of engagement with said ratchet wheel, and a friction member associated with the connection between said line-space lever and said pawl for operating said pawl. 100
5. In a typewriting machine, the combination with the platen carriage, of a platen roll mounted thereon, a ratchet wheel carried by said platen roll, a line-space lever pivotally mounted upon the platen carriage, a pawl pivotally mounted upon said line-space lever and normally held adjacent but out 45 of contact with the teeth of said ratchet wheel, a friction member associated with the connection between said line-space lever and said pawl, whereby said pawl will be instantly thrown into engagement with the teeth of said ratchet wheel upon an actuation of said line-space lever and will likewise 110 be instantly disengaged from said teeth upon the return movement of said line-space lever, and means connected with said pawl adapted to return the same to a position in adjacency with the teeth of said ratchet wheel. 115
6. In a typewriting machine, the combination with the platen carriage, of a platen roll mounted thereon, a ratchet wheel carried by said platen roll, a line-space lever mounted to swing upon the platen carriage, 50 whereby the paper will be fed, a line-space 120

- a pawl pivotally mounted upon the line-space lever, a friction member associated with the connection between said line-space lever and said pawl, means for holding said 5 pawl adjacent the teeth of said ratchet wheel, and a gage stop rotatably mounted upon said line-space lever and adapted to engage with said pawl when said line-space lever is actuated, whereby the throw of said 10 pawl may be regulated.
10. In a typewriting machine, the combination with the platen carriage of a platen roll mounted thereon, a ratchet wheel carried by the platen roll, a line-space lever 15 pivotally mounted upon the platen carriage, a pawl pivotally mounted upon said line-space lever, said pawl having a plurality of notches formed in the back thereof, and a stop gage adjustably mounted upon said 20 line-space lever and adapted to engage with one of said notches, when the line-space lever is actuated to thereby limit the throw of said pawl in accordance with the adjustment of said gage.
15. 11. In a typewriting machine, the combination with the platen carriage, of a platen roll mounted thereon, a ratchet wheel mounted upon the shaft of said platen roll, a line-space lever pivotally mounted upon the platen carriage, a line-space pawl mounted upon 25 said lever, and an adjustable stop gage mounted upon said line-space lever normally out of engagement with said pawl adapted when said line-space lever is actuated to engage with different portions of said pawl 30 to limit the throw thereof.
20. 12. In a typewriting machine, in combination, a movable paper carrier, line spacing mechanism therefor comprising a lever and pawl pivoted thereto, and a friction ring associated with the pivotal connection to hold the pawl in a normal fixed relation thereto.
25. 13. In a typewriting machine, in combination, a paper carrier, line spacing mechanism comprising a lever and pawl pivoted thereto, and a resilient device associated 30 with the pivotal connection between said parts adapted yieldingly to hold the pawl 50 in normal fixed relation thereto.
35. 14. In a typewriting machine, the combination with the platen carriage, of a platen roll journaled therein, a peripherally notched ratchet wheel mounted upon the 40 shaft of said platen roll, a detent engaging the peripheral notches of said ratchet wheel to register the platen roll after rotation, a spring support upon which said detent is mounted adjustably secured to said carriage, 45 and a lever mounted upon the shaft of said platen roll and having a plurality of notches, one of said notches engaging the support of said detent when the latter is in engagement with the ratchet wheel, said 50 lever being adapted to be swung to engage the other notch thereof with said support, whereby said detent is lifted from engagement with said ratchet wheel.
40. 15. In a typewriting machine, the combination with the platen carriage, of a platen mounted thereon, a ratchet wheel carried by the shaft of said platen roll, a line-space lever pivotally mounted upon the platen carriage, a line-space pawl mounted upon 55 said lever, and an adjustable stop gage mounted upon said line-space lever normally out of engagement with said pawl adapted when said line-space lever is actuated to engage with different portions of said pawl 60 to limit the throw thereof.
45. 16. In line spacing mechanism for typewriting machines, in combination, a paper carrier, a member carried thereby and arranged to be operated upon to move said 65 paper carrier for line spacing, an actuating lever, and a pawl mounted thereon movable thereby into and out of engagement with said member solely by its frictional connection with said lever.
50. In testimony whereof I affix my signature, in the presence of two witnesses.
- JOSEPH ALBERT RONCHETTI.
